AIR DRAFT TIMING AND VOLUME CONTROL

Charles M. Helyar, Saint Vital, Manitoba, Canada

Application April 30, 1942, Serial No. 441,248

12 Claims. (Cl. 110—72)

1

My invention relates to an air draft timing and volume control assembly particularly but not exclusively for automatic stokers, designed to be located within the air duct leading to the retort thereof, an object of this invention being to provide a device of the character described, by the use of which, at the commencement of each cycle of stoker operation, the fuel bed will be given an opportunity to kindle without the intervention of a forced draft, until there is sufficient incandescence and burning strength in the fuel bed to warrant the introduction of a gradually increasing volume of air.

A further object of my invention is to provide an assembly of the character herewithin described, by the use of which, at the conclusion of a cycle of stoker operation, the fuel bed may continue to draw a natural draft through the stoker air duct for a predetermined period of time, such draft being however, gradually obstructed and eventually closed off.

A further object of my invention is to provide an assembly of the character herewithin described which is of eminently simplified construction, can readily be installed by service men following simplified instructions, can readily be adjusted to the conditions of any stoker, will give long service and cannot readily become out of order.

With the above more important objects in view and such other minor objects as may appear as the specification proceeds, my invention consists essentially in the arrangement and construction of parts all as hereinafter more particularly described, reference being had to the accompanying drawings, in which:

Figure 1 is a side elevation of my air draft timing and volume control assembly, in situ with both dampers closed.

Figure 2 is similar to Figure 1 but showing both dampers fully open.

Figure 3 is an end elevation of my assembly.

Figure 4 is a perspective detail illustrating the structure employed to adjust my control damper.

Figure 5 is a detail illustrating my air discharge elbow and associated valve.

Figure 6 is a perspective detail illustrating the structure employed to adjust my measuring damper.

In the drawings like characters of reference indicate corresponding parts in the different figures.

According to conventional practice in the construction and operation of automatic stokers, the fan is synchronised to start up simultaneously with the motor operating the coal feed screw, no

2

means being provided to regulate the volume of air fed to the dormant fire bed.

As a result, the violent kindling action of a full head of air under forced draft, can, and sometimes does have the effect of extinguishing the fire completely, blowing the remaining incandescent particles up the chimney. When this extreme is not reached, a considerable quantity of fly-ash is blown about inside the fire box to settle on the castings and effectively insulate the same against the transmission of heat.

Dealing with the effect upon a fire bed, of the shutting off of the fan at the conclusion of a cycle of stoker operation, I would explain that two conventional expedients are followed in construction and installation. The first is to provide a heavily weighted damper within the air duct leading to the retort, so that immediately after the fan stops, the damper will drop, being sufficiently heavy to resist being lifted by natural chimney draft. The other is to provide no damper in the duct, which permits of the continuance of a natural draft after the stopping of the fan.

The first expedient results in the fire being suddenly banked at a moment when valuable volatiles are being liberated, these volatiles thus, being deprived of the necessary oxygen required to ignite the same. With the second expedient, a fire can burn itself out before the next cycle of stoker operation commences.

My assembly is therefore designed to obstruct the passage of air from the fan for a short period immediately following the commencement of a cycle of stoker operation so as to give the fuel bed an opportunity to kindle while in its initial attenuated state, thereafter permitting the passage of a "nursing" draft as the heat of the fuel bed increases and the fire grows stronger, and from there gradually increasing as more coal is fed.

In conventional stoker practice, it should be understood that a fixed damper is provided in the forced air duct, the damper being adjusted to each particular job. As an arbitrary example, it may be said that such damper is adjusted to cut off four fifths of the area of the duct.

It therefore follows, that when a thick and possibly dense fuel bed has been built up, that such fuel bed will resist the penetration of a forced draft. It is therefore necessary to increase the volume of air so as to overcome obstructions, but this cannot be done with a fixed damper and consequently valuable products of

combustion liberated, cannot dissipate their full thermal efficiency owing to lack of oxygen.

With my assembly, when a fixed, dense and hot fuel bed has been created, I am able to overcome the resistance to the passage of air by permitting an increase in the volume of air which will pass through the duct, a volume which is only limited by the capacity of the fan and thus the fuel bed of an automatic stoker to which my assembly has been fitted, will never be over-nourished or undernourished with air to impair its thermal efficiency.

In view of the foregoing brief résumé comparing my assembly with conventional practice, a résumé which could be considerably amplified, I will proceed to describe the construction of my assembly.

At any convenient point upon the length of a stoker duct 1, I locate an intermediately journaled volume regulating damper 2 capable of sealing one side of the duct from the other completely. It is generally found convenient when inserting a damper in a duct to frame the same as by means of the frame 3, which, however, I do not claim to be part of my invention. A small stop 4 may also be provided to prevent rotation of the damper 2 in a counterclockwise direction beyond the limits imposed by the stop.

One of the trunnions 5 of the damper 2 projects substantially beyond the side wall 6 of the duct, a quadrant plate 7 being secured to the end thereof for rotation therewith and with the plate. A sleeve 8 is also freely mounted upon the trunnions between the quadrant plate 7 and the wall 6, a radial quadrant lock 9 of the configuration clearly illustrated in the accompanying Figure 4, being secured for rotation with the sleeve 8. This quadrant lock, it will be seen, terminates at the lower end thereof in a reverse-angled portion 10 provided with the set-screw 11 which is capable of clamping onto the arcuate edge of the plate 7 at any desired point so that the sleeve 8 and the trunnions, and consequently the damper too, moves as a unit.

Secured at its inner end to the sleeve 8 is a bi-metallic heat motor 12 formed of spiral bi-metal tape and substantially like a spiral-type thermostat. The outer end 13 of the motor 12 is anchored at a convenient point upon the perimeter of a fairly massive heat retaining ring 14 which surrounds the motor, this ring being preferably made of cast iron or some other substance capable of retaining heat fairly efficiently. This ring is clamped to the wall 6.

An offset portion 15 of the ring 14 is provided with the passage 16, which passage opens onto the internal circumference of the ring at one end thereof, right angling at the other end thereof as I have indicated by the chain-line ring 17 in Figure 1 and by the parallel chain lines 17 in Figure 5, and opening upon the posterior surface 18 of the offset portion and in alignment with an air discharge port 19 which includes an aperture (not shown) in the wall 6 and an upwardly directed elbow provided with the vertically movable valve 20.

Also within the duct 1 but spaced from the damper 2 and upon the retort side thereof is an air flow responsive vane 21 normally biased to the position illustrated in Figure 1, and also preferably mounted within a frame 22 similar to the frame 3, a stop 23 being provided similar to the stop 4.

This vane will preferably be mounted to swing about a line above its central horizontal axis,

the trunnions projecting on either side of this vane, also being journaled in the frame 23, the opposite side wall of the duct, or both.

The trunnion 24 projects beyond the wall 6 similarly to the trunnion 5, a quadrant plate 25 being secured to the end thereof for rotation therewith similarly to the quadrant plate 7. A sleeve 26 similar to the sleeve 8 is freely mounted on the trunnion between the plate 25 and the wall, a quadrant lock 27 similar to the quadrant lock 9 being secured for rotation with the sleeve so that the foregoing parts may be caused to rotate as a unit.

Upon the sleeve 26 is a trip rod 28 of the configuration best illustrated in the accompanying Figure 6, capable of intercepting the lever 29 best illustrated in Figures 1, 2 and 6, provided with the right angled portion 29', which lever is journaled in the bearing 30, being angulated adjacent the bearings and therefore projecting through the wall 6 into the interior of the duct where it angles backwardly as I have indicated at 31 in Figures 1 and 2, finally being angulated as at 32, transversely of the duct and as best illustrated in Figure 5 extending freely through a transverse drilling in the head 33 of the valve 20 so that rotation of the lever in a clockwise direction with respect to the accompanying Figures 1 and 2, will lift the valve.

Secured to the wall 6 below the ring 14 is an electric coil 34 through which current is designed to pass upon the commencement of a cycle of stoker operation to heat the ring 14 and the heat motor 12, and finally, those parts of the foregoing structure which are positioned upon the outer side of the duct 1, are enclosed within the housing 35, the end wall 36 of this housing being provided with the air escape aperture 37 for the purpose presently to be described.

Proceeding now to describe the operation of my assembly, I would explain that immediately upon the commencement of a cycle of stoker operation, the coil 34 commences to heat up and radiate its heat against the ring 14. However, a certain length of time will elapse before the ring has absorbed sufficient heat to transmit any to the bi-metallic heat motor or coil 12 and during that time, the fuel bed in the stoker retort is kindling naturally rather than being blown apart and struggling against a violent draft of air.

Eventually, the coil or bi-metal tape of the motor 12 commences to lengthen and unwind opening the damper 2 very slowly and gradually permitting air therewith.

The air flowing therewith will gradually acquire sufficient volume to lift the vane 21, and at this point, I would specifically explain, as will be clearly noted from Figures 1 and 2, that the vane 21 does not entirely seal the duct 1 as does the damper 2 when closed, the upper and lower horizontal edges 38 and 39 of the vane 21 providing the narrow transverse spaces 40 and 41 at top and bottom through which a small volume of air may pass without raising the damper.

At a certain stage, after the fuel bed has become replenished with coal and the same is giving off its products of combustion freely, the control damper 2 will have rotated almost as far as I have shown in the accompanying Figure 2, thus permitting the passage of a certain volume of air to lift the vane 21 almost as far as I have shown it in the same figure. The accumulated heat within the ring 14 and the continued radiation of heat from the coil 34, will eventually move

the control damper still further as for example, to the position as actually illustrated in the accompanying Figure 2 at which point the increased volume of air will cause the vane 21 to rise still further, and to the point actually shown where the trip rod 28 will intersect the lever 29, rotating the same to a small extent and causing the valve 20 to open.

Opening of the valve 20 permits the escape of air through the port 19, through the passage 16 to impinge upon the motor 12 tending to cool the same, thereby contracting it and causing the damper plate 2 to rotate slowly in the opposite and closing direction. In this way, it will be seen that I have provided an accurate means for governing and controlling the maximum volume of air to be permitted into the retort. Air discharged through the port 19 may escape through the aperture 31 in the end wall 36 of my casing 35.

As I have previously indicated, a considerable volume of air at substantial pressure is required to penetrate through a dense, thick fuel bed—a greater volume, that is, than would ever practicably be permitted with a fixed damper, the position of which is a compromise to provide at least reasonable efficiency under a variety of fire bed conditions.

Therefore, it is to be understood that when a fuel bed is well filled with coal, giving up its volatiles freely, my control damper 2 is in such position that it is permitting a greater volume of air to pass and force its way through the bed than would be the case with a fixed damper, the air discharge port 19 and associated valve being provided to check the damper 2 against permitting the admission of an even greater, and excessive volume of air, as the motor 12 gets hotter and increases in length.

At the conclusion of a cycle of stoker operation, at which time the fan comes to rest, it will be recognized that my control damper 2 is open to the maximum extent, and the same will only close at a very slow rate of speed, as the heat motor and the heavy cast ring 14 surrounding it, give up their heat so that a brisk natural draft may continue to be indrawn into a fire bed, the oxygen therein being utilized to ignite the volatiles as they continue to be liberated but at a decreasing rate.

Referring to the adjusting means associated with my damper and vane and including the quadrant plates 7 and 25 et seq. respectively, it will readily be understood by reference to the accompanying Figures 1 and 4 for instance, that rotation of the quadrant lock 9 in a clockwise direction following the loosening of the screw 11, around the quadrant plate, will increase the tension of the motor 12. Conversely, rotation of the arm 9 in the opposite direction, will slacken the motor, and in this connection, I desire to explain that I generally prefer that my motor be so adjusted that the damper 2 is caused to bear against the stop 4 with a certain amount of pressure when in closed position, so that it will not commence to rotate immediately the bi-metal tape of the motor commences to deform responsive to the adjacent heat source.

As to my flow responsive vane 21 and air discharge valve 19, it will readily be recognized that rotation of the quadrant lock 27 on the quadrant plate 25, together with the sleeve 26 and the trip rod 28, will control the point at which the valve 20 opens responsive to the action of the rod 29, and so, with these adjustments on each of my

plate and vane, I am able to provide accurately for every installation.

In conclusion, although the title of this specification directs my invention to its use for automatic stokers, I desire to explain that the same would also be practicable and useful in certain other industrial arts such for example as in the drying of a mass of material varying in density. I therefore do not wish this specification to be interpreted as limiting my rights under this patent to the use of my invention on automatic stokers but only as limited by the appended claims.

Since various modifications can be made in my invention as hereinabove described and many apparently widely different embodiments of same made within the scope of the claims without departing from such spirit and scope, it is intended that all matter contained in the accompanying specification shall be interpreted as illustrative only and not in a limiting sense and I desire only such limitations placed thereon as are specifically expressed in the accompanying claims.

What I claim as my invention is:

- 25 1. An air draft timing and volume control for automatic stokers, comprising in combination with the air duct thereof a rotatable volume regulating damper and a rotatable flow responsive vane normally biassed to one position and movable from such position by an amount dependent on the flow therewith, said vane being positioned in spaced relationship with respect to said volume regulating damper, within said air duct and upon the downstream side of said regulating damper, the area of said vane being less than the right angled transverse area of said duct, a heat motor connected to said regulating damper and governing the movement thereof so as to permit an increased flow therewith as the temperature of said motor increases, a coil for heating said motor upon the commencement of a cycle of stoker operation, means for cooling said motor upon the opening of said vane to a predetermined extent, a trunnion rotatable with at least said damper or said vane, a plate secured for rotation to and with said trunnion, a loose sleeve on said trunnion, and means projecting from said sleeve, said means being secured for unitary movement to and with said sleeve for locking said plate and said sleeve in a plurality of selected positions so that said plate and sleeve may rotate as a unit.
- 30 2. An air draft timing and volume control comprising in combination with an air duct, a volume regulating damper, a flow responsive vane normally biassed to one position and being movable from such position by an amount dependent on the flow therewith, said vane being positioned in spaced relation with respect to said volume regulating damper, within said air duct, a heat motor connected to said regulating damper and governing the movement thereof so as to permit an increased flow therewith as the temperature of said motor increases, means for periodically heating said motor, and automatically operable means for cooling said motor upon the movement of said vane from its normal position a predetermined extent.
- 35 3. An air draft timing and volume control comprising in combination with an air duct, a volume regulating damper, a flow responsive vane normally biassed to one position and being movable from such position by an amount dependent on the flow therewith, said vane being positioned in spaced relation with respect to said volume regulating damper, within said air duct, said vane be-

ing located upon the downstream side of said regulating damper, a heat motor connected to said regulating damper and governing the movement thereof so as to permit an increased flow therewith as the temperature of said motor increases, means for periodically heating said motor, an air discharge port in said air duct constructed and arranged to direct its discharging air onto said motor, together with an associated normally closed valve, and means designed so as to open said valve and permit air from within said duct to impinge upon and cool said motor when said vane is moved from its normal position a predetermined extent.

4. An air draft timing and volume control comprising in combination with an air duct, a volume regulating damper, a flow responsive vane normally biassed to one position and being movable from said position by an amount dependent on the flow therewith, said vane being positioned in spaced relation with respect to said volume regulating damper, within said duct, said vane being positioned upon the downstream side of said regulating damper, a heat motor connected to said regulating damper and governing the movement thereof so as to permit an increased flow therewith as the temperature of said motor increases, means for periodically heating said motor and an air discharge port in said air duct constructed and arranged to direct its discharging air onto said motor together with an associated valve normally closing said ducts, said valve being operable to open position by the movement of said vane from its normal position a predetermined extent thereby permitting the air from within said duct to impinge upon said motor to cool the same.

5. An air draft timing and volume control comprising in combination with an air duct, a volume regulating damper, a flow responsive vane normally biassed to one position and being movable from said position by an amount dependent upon the flow therewith, said vane being positioned in spaced relation with respect to said volume regulating damper, within said duct, said vane being positioned upon the downstream side of said regulating damper, a heat motor connected to said regulating damper and governing the movement thereof so as to permit an increased flow therewith as the temperature of said motor increases, means for periodically heating said motor, an air discharge port in the form of an elbow in one wall of said duct constructed and arranged to direct its discharging air onto said motor, a valve normally closing said port within said duct, a lever connected to said valve, said lever being rotated by the movement of said vane when the latter is moved from its normal position a predetermined extent to open said valve, thereby permitting the escape of air from within said duct through said port to impinge upon said motor and cool the same.

6. An air draft timing and volume control comprising in combination with an air duct, a volume regulating damper, a flow responsive vane normally biassed to one position and being movable from said position by an amount dependent on the flow therewith, said vane being positioned in spaced relation with respect to said volume regulating damper, within said duct, said vane being positioned upon the downstream side of said regulating damper, a heat motor connected to said regulating damper and governing the movement of same so as to permit an increased flow therewith as the temperature of said motor increases,

a heat radiating ring around said motor, means for periodically heating said ring and thereby said motor, and means for cooling said motor upon the movement of said vane from its normal position a predetermined extent.

5 7. An air draft timing and volume control comprising in combination with an air duct, a volume regulating damper, a flow responsive vane normally biassed to one position and being movable from said position by an amount dependent upon the flow therewith, said vane being positioned in spaced relation with respect to said volume regulating damper, within said duct, said vane being located upon the downstream side of said regulating damper, a heat motor connected to said regulating damper and governing the movement thereof so as to permit an increased flow therewith as the temperature of said motor increases, a heat radiating ring around said motor, means for periodically heating said ring and thereby said motor, and an air discharge port in said air duct constructed and arranged to direct its discharging air onto said motor together with an associated valve normally closing said ducts, said valves being operable to open position by the movement of said vane from its normal position a predetermined extent, thereby permitting air from within said duct to impinge upon said motor to cool the same.

30 8. An air draft timing and volume control comprising in combination with an air duct, a volume regulating damper, a flow responsive vane normally biassed to one position, and being movable from such position by an amount dependent on the flow therewith, said vane being positioned in spaced relation with respect to said volume regulating damper, within said duct, said vane being located upon the downstream side of said regulating damper, a heat motor connected to said regulating damper and governing the movement thereof so as to permit an increased flow therewith as the temperature of said motor increases, a heat radiating ring around said motor, means for periodically heating said ring and thereby said motor, an air discharge port in the form of an elbow in one wall of said duct constructed and arranged to direct its discharging air onto said motor, a valve normally closing said port within said duct, a lever connected to said valve, said lever being rotated by the movement of said vane when the latter is moved from its normal position a predetermined extent to open said valve thereby permitting the escape of air from within said duct through said port to impinge upon said motor and cool the same.

45 9. An air draft timing and volume control comprising in combination with an air duct, a volume regulating damper, a flow responsive vane normally biassed to one position and being movable from such position by an amount dependent upon the flow therewith, said vane being positioned in spaced relation with respect to said volume regulating damper, within said duct, said vane being positioned upon the downstream side of said regulating damper, said vane being supported on projecting trunnions, a plate secured for rotation to one of said trunnions, a sleeve on the trunnion to which said plate is connected, said sleeve being interposed between said vane and said plate, a radial lock securing said plate to said sleeve, a trip rod also secured to said sleeve, a heat motor connected to said regulating damper and governing the movement thereof so as to permit an increased flow therewith as the temperature of said motor increases, means for periodically heat-

ing said motor, an air discharge port in the form of an elbow in one wall of said duct constructed and arranged to direct its discharged air onto said motor, a valve normally closing said port within said duct, a lever connected to said valve, said lever being engaged by said trip rod upon the rotation thereof, together with said lock, plate and vane, a predetermined extent to open said valve and permitting the passage of air from within said duct through said elbow to impinge on said motor and cool the same.

10 15 20 25

10. An air draft timing and volume control comprising in combination with an air duct, a volume regulating damper positioned therewithin, a heat motor connected to said damper upon the external side of said duct and governing the movement of said damper so as to permit an increased flow therewith as the temperature of said motor increases, an air discharge port in the wall of said duct constructed and arranged to direct its discharging air onto said motor, a valve normally closing said port, means for periodically heating said motor, and automatically operable means for opening said valve to permit air to escape through said port and impinge on said motor to cool the same and thereby move said damper towards or into the closed position following the opening of said damper a predetermined maximum extent.

11. An air draft timing and volume control comprising in combination with an air duct, a volume regulating damper positioned within said air duct, a heat motor connected to said damper upon the external side of said duct and govern-

ing the movement of said damper so as to permit an increased flow therewith as the temperature of said motor increases, a heat radiating ring around said motor, an air discharge port in the wall of said duct constructed and arranged to direct its discharging air onto said motor, a valve normally closing said port, means for periodically heating said ring and thereby said motor, and automatically operable means for opening said valve to permit air to escape through said port and impinge on said motor to cool the same and thereby move said damper towards or into the closed position following the opening of said damper a predetermined extent.

12. An air draft timing and volume control comprising in combination with an air duct, a volume regulating damper, a flow responsive vane normally biased to one position and being movable from such position by an amount dependent on the flow therewith, said vane being positioned in spaced relation with respect to said volume regulating damper, within said air duct, said vane being positioned upon the downstream side of said regulating damper, a heat motor connected to said regulating damper and governing the movement thereof so as to permit an increased flow therewith as the temperature of said motor increases, means for periodically heating said motor, means for cooling said motor upon the movement of said vane from its normal position a predetermined extent, the area of said vane being less than the right angled transverse area of said duct.

CHARLES M. HELYAR.
